PENNSYLVANIA.

COMPRESSION AND SUCTION DEVICE.

1,142,544.

Specification of Letters Patent.

Patented June 8, 1915.

Application filed December 29, 1913. Serial No. 809,412.

To all whom it may concern.

Be it known that we, JAMES B. VERNON and MARTIN J. SIEFFERT, who are respectively residents of Pittsburgh and Wireton

5 P. O., both in the county of Allegheny and State of Pennsylvania, have invented a new and useful Improvement in Compression and Suction Devices, of which the following is a specification.

10 This invention relates to apparatus for producing suction or compression, or rotary pumps, and particularly to that class of pumps embodying a chamber in which is eccentrically mounted a rotary hub or piston carrying a number of movable blades which sweep around a crescent shaped space between the piston and outer casing and force the fluid therethrough.

15 The object of the invention is to provide 20 a pump of the type described which is more efficient than prior pumps, and in which the movable blades are held yieldingly against the end walls or heads of the casing, but without binding thereon, so that leakage of air around the blades is prevented.

25 A further object of the invention is to provide a pump in which the blades are each formed of a plurality of members, part 30 of which are held yieldingly in contact with each end wall or head of the casing, and all of which are held yieldingly in contact with the side casing wall, so as to produce a perfectly sealed joint between the casing and all of the edges of the blades.

35 A further object of the invention is to provide, in a pump of the type described, means for producing a flow of lubricant down around the side faces of the piston blades, or the members forming the same, 40 so as to thoroughly lubricate all of the moving parts of the pump, and insure a tight and efficient seal between the edges of the blades and the casing, and thereby increase the efficiency of the pump.

45 Further objects of the invention are in part obvious and in part will appear more in detail hereinafter.

50 In the drawings Figure 1 represents a longitudinal sectional view, on the line 1—1, Fig. 2, of a pump embodying the invention, the lower half of the hub or piston being shown in side elevation; Fig. 2 is a sectional elevation on the line 2—2, Fig. 1, looking in the direction of the arrows; Fig. 55 3 is a perspective view of the hub or piston,

two of the blades being omitted; Fig. 4 is a perspective view of a single blade member, and Fig. 5 is a side elevation of a piston blade.

Referring to the drawings, which illustrate one of many forms of the invention, 60 Fig. 1 indicates a suitable casing having therein a cylindrical bore or chamber closed at its ends by the heads 2 and 3. One of the end heads may be integral with the cylindrical portion or side wall of the casing, but in the form shown both of said heads are separate and are clamped to the end faces of the cylindrical portion by tap screws or bolts 4. The rotor comprises a hub or piston 5, which has a large cylindrical portion fitting snugly between the end heads of the casing, and which at one side, as at 6, bears against the side casing wall. This hub or piston is provided with a plurality of circumferentially spaced radial slots or sockets 7, three being shown, in each of which is mounted a movable piston blade. Each blade is pressed yieldingly outward against the side casing wall by one or more springs 8, as shown in Fig. 1, said springs bearing at their inner ends against the bottoms of the slots 7 and having their outer ends lying in notches 9 in the inner edges of the piston blades. These springs allow the blades to move radially in the slots 7 as they travel around the crescent shaped chamber 10, lying between the piston and the side casing wall. The piston may be rotated in any suitable manner and as shown is provided 80 with end journal portions 11 extending into bearings in the heads of the casing. One of said journals is extended beyond its bearing for connection to the power driving means, and is shown as provided with fast 85 and loose pulleys 12 and 13 for a driving belt. The particular arrangement of the driving means is not essential. The lower half of the casing is enlarged and cored out 90 to form two chambers 14 and 15. Chamber 14 is on the induction side of the casing and is provided with a connection 16 which may lead to any suitable place where it is desired to produce suction. Said induction chamber 14 communicates with the crescent shaped chamber 10 through a plurality of ports or openings 17 in the side casing wall. The ejection chamber 15 is provided with 95 a connection 18 leading to any suitable location where it is desired to produce pressure, 100 110

such as an ordinary blowpipe. It communicates with the eduction end of the chamber 10 through one or a plurality of ports or openings 19 in the side casing wall. Ports or openings 17 and 19 are elongated circumferentially of the casing, so that they form bypasses around the piston blades as they travel past said ports and prevent the flow of fluid into and out of the compression chamber from being interrupted or intermittent and also equalize the pressure on opposite sides of each piston blade when it approaches or recedes from the end of the crescent shaped chamber 10. This prevents back pressure or suction on the piston blades and produces a steady and uninterrupted flow of fluid through the pump, thereby increasing its efficiency and maintaining constant maximum compression or suction effect.

In order to increase efficiency means is provided for circulating through the machine a continuous stream of liquid, which may be glycerin or some similar material, but is preferably an oil and thereby serves as a lubricant. As shown in the drawings, eduction chamber 15 is provided with an outlet 20 at its lowest point, from which a suitable conduit or pipe, indicated at 21, leads to an inlet 22 at or near the top of induction chamber 14. Said conduit may be provided with any suitable form of regulating valve 23 for controlling the flow of liquid through the pump.

In use of the apparatus a quantity of liquid, such as oil, is poured into the chamber 15. When the hub or piston is rotated a suction effect is produced in chamber 14, thereby withdrawing the oil from chamber 15 and causing it to flow through conduit 21 into chamber 14. The oil is carried into the compression chamber 10 with the inflowing air and penetrates into all crevices of the moving parts and covers every surface thereof, so that it effectively seals the spaces between the piston blades and the cylinder walls and therefore prevents the escape of air around the blades.

In pumps of this character, as heretofore constructed, it has been necessary to form the piston blades with great accuracy, as they must not only be held yieldingly against the side wall of the cylindrical casing, but must also be tightly sealed against the end heads of the casing. Inaccuracies in the shape of the casing or in the length of the piston blades are likely to cause the blades to bind in the casing or else leave an unsealed space between their end edges and the end heads of the casing. In order to prevent the blades from binding in the casing and to insure a tight seal, we preferably form each piston blade of a plurality of members which are movable endwise with respect to each other, one mem-

ber of each blade being forced yieldingly against one end head of the casing. In the form shown each blade comprises two members 24, placed side to side, and which are preferably formed of fiber or some suitable hard material which does not wear appreciably or produce a material heating effect. Each of said members is slightly shorter than the distance between the end casing heads so that it cannot bind therebetween. The blade members are furthermore each provided with a longitudinal slot or opening 25 and a side lug or projection 26 which projects into and moves in the longitudinal slots 25 of the other member. Slots 25 are made long enough so that there is a space between the two side projections 26, said space being provided for a compression spring 27 which forces the blades apart endwise. Each blade is consequently held yieldingly, by the spring 27, in contact with one end head of the casing, and inequalities in the length of the chamber 10 are taken up by relative endwise movement between the blade members of each pair. The inter-engaging projections 26 and slots 25 form guides which prevent other than longitudinal motion between the blade members so that they move together radially inwardly and outwardly, as before described.

To insure thorough lubrication of the blades, and to also insure the penetration of the lubricating liquid into all of the crevices and between all contacting surfaces within the pump, we preferably form each piston blade, or the members composing the same in such manner as to continuously pump oil down along the side surfaces of the blades. As shown the outer edges of the slots or sockets 7 are beveled or chamfered, as at 28, to form pockets which trap and hold the lubricating material. The contacting inner side faces of the blade members of each pair are smooth and uninterrupted, but their outer side faces, which contact with the side walls of the slots 7, are provided with suitable pockets, shown as longitudinal grooves or channels 29, the inner surfaces of which are beveled or inclined, as at 30, and the outer surfaces of which are straight or square, as shown at 31, so that in end view the grooves in the blade look like a series of ratchet teeth, as shown in Fig. 4. One or more of the pockets or grooves 29 are located near the outer edge of the piston blades, so that when each blade reaches the widest point in the chamber 10, as shown at the top in Fig. 2, these pockets or grooves are entirely outside of the slots 7. Each time the blades move inwardly the oil pockets 29 take up a part of the oil trapped in the pockets 28 and carry it downwardly along the side walls of the slot 7. On the outward movement of the piston blade some of the oil is left be-

hind and is scraped up and collected by the next pocket 29 on the next inward movement of the blade. The pockets 29 therefore produce a pump effect, carrying the 5 lubricating material downwardly along the contacting side faces of the blades 24 and slots 7 by a step by step movement, so that it is forced clear to the bottom of the slots 7 and works its way out at the ends thereof 10 into the spaces between the end faces of the hub or piston and the end heads of the casing. This insures thorough lubrication of all working surfaces and a tight seal between the end and side edges of the blades 15 and the casing wall. Some of the oil is continuously discharged from the pressure chamber through the eduction ports 19 and is collected in the chamber 15. This oil however, drains out through the outlet 20 20 and is carried back to the induction side of the casing so that the oil is circulated continuously through the pump.

The machine described may be used for various purposes, either for producing suction or compression. It may be used for 25 dental purposes or for cleaning, but is also adapted for producing compression for operating blow-pipes or like devices. It is very efficient and produces a continuous and 30 uninterrupted suction or compression effect of maximum efficiency. It is self lubricating so that it will run steadily and continuously or may be operated intermittently over long periods of time without attention 35 on the part of the operator, so that it is

particularly adapted for use by unskilled operators or in places where it is either unlikely to receive attention or is more or less inaccessible. It will therefore stand 40 considerable neglect or even hard or rough usage without material loss of efficiency.

What we claim is:

1. A machine of the character described, comprising a casing provided with a chamber, a rotor eccentrically located in said 45 chamber, and provided with a longitudinal slot beveled at its edge to form an oil pocket, a blade movably mounted in said slot, and a pocket in the side face of said blade arranged to pass said oil pocket during each rotation of the rotor and carry oil 50 down into the rotor slot.

2. A machine of the character described, comprising a casing provided with a chamber, a rotor eccentrically located in said 55 chamber and provided with a longitudinal slot beveled at its edge to form an oil pocket, a blade movably mounted in said slot and provided with a longitudinal groove arranged to pass said oil pocket during each rotation of said rotor and carry oil 60 down into said slot.

In testimony whereof, we have hereunto set our hands.

JAMES B. VERNON.
MARTIN J. SIEFFERT.
